[57] CLAIM

The ornamental design for a desktop computer workstation, as shown and described.

DESCRIPTION

FIG. 1 is a front elevational view of a desktop computer

workstation in accordance with a first preferred embodiment of the present invention, showing a monitor screen in an open position;

FIG. 2 is a right side elevational view of the computer workstation of FIG. 1, with the monitor screen in an open and rearward position, the left side elevational view being a mirror image thereof;

FIG. 3 is a right side elevational view of the computer workstation of FIG. 1, with the monitor screen in an open and intermediate position, the left side elevational view being a mirror image thereof;

FIG. 4 is a right side elevational view of the computer workstation of FIG. 1, with the monitor screen in an open and forward position, the left side elevational view being a mirror image thereof;

FIG. 5 is a right side elevational view of the computer workstation of FIG. 1, with the monitor screen in a closed position, the left side elevational view being a mirror image thereof;

FIG. 6 is a rear elevational view of the computer workstation of FIG. 1;

FIG. 7 is a top plan view of the computer workstation of FIG. 1;

FIG. 8 is a bottom plan view of the computer workstation of FIG. 1;

FIG. 9 is a front elevational view of a computer workstation in accordance with a second preferred embodiment of the present invention, showing a monitor screen in an open position;

FIG. 10 is a right side elevational view of the computer workstation of FIG. 9, with the monitor screen in an open and rearward position, the left side elevational view being a mirror image thereof;

FIG. 11 is a right side elevational view of the computer workstation of FIG. 9, with the monitor screen in an open and intermediate position, the left side elevational view being a mirror image thereof;

FIG. 12 is a right side elevational view of the computer workstation of FIG. 9, with the monitor screen in an open and forward position, the left side elevational view being a mirror image thereof;

FIG. 13 is a right side elevational view of the computer workstation of FIG. 9, with the monitor screen in a closed position, the left side elevational view being a mirror image thereof;

FIG. 53 is a right side elevational view of the computer workstation of FIG. 49, with the monitor screen in a closed position, the left side elevational view being a mirror image thereof;

FIG. 54 is a rear elevational view of the computer workstation of FIG. 49;

FIG. 55 is a top plan view of the computer workstation of FIG. 49;

FIG. 56 is a bottom plan view of the computer workstation of FIG. 49; and,

FIG. 57 is a left side elevational view of the computer workstation of FIG. 49.
